[57] CLAIM

The ornamental design for a dual compartment bottle, as shown.

DESCRIPTION

FIG. 1 is a perspective view showing the top, front and right side of a dual compartment bottle embodying my new design;

FIG. 2 is a left side elevational view thereof, with the right side being a mirror image of the left side as shown;

FIG. 3 is a top plan view thereof;

FIG. 4 is a front elevational view thereof, with the rear elevation being a mirror image of the front as shown; and,

FIG. 5 is a bottom plan view thereof.

FIG. 1

FIG. 2

FIG. 3

FIG. 4

FIG. 5
